UNITED STATES PATENT OFFICE

153,186

DESIGN FOR A BASEMAN'S MITT

William J. Sonnett, Ada, Ohio, assignor to Ohio-Kentucky Manufacturing Company, Ada, Ohio, a corporation of Ohio

Application December 17, 1946, Serial No. 135,566

Term of patent 14 years

(Cl. D3—11)

To all whom it may concern:

Be it known that I, William J. Sonnett, a citizen of the United States and a resident of Ada, in the county of Hardin and the State of Ohio, have invented a new, original, and ornamental Design for a Baseman's Mitt, of which the following is a specification, reference being made to the accompanying drawings, forming a part thereof.

Fig. 1 is a perspective front view of a baseman's mitt embodying my new design.

Fig. 2 is a perspective rear view of the baseman's mitt shown in Fig. 1.

I claim:

The ornamental design for a baseman's mitt, substantially as shown.

WILLIAM J. SONNETT.
